UNITED STATES PATENT OFFICE.

JOSEPH G. KINCAID, OF HIAWATHA, KANSAS.

WASHING-MACHINE.

No. 822,371.

Specification of Letters Patent.

Patented June 5, 1906.

Application filed November 18, 1904. Serial No. 233,304.

To all whom it may concern:

Be it known that I, JOSEPH G. KINCAID, a citizen of the United States, residing at Hia-
watha, in the county of Brown and State of
5 Kansas, have invented a new and useful
Washing-Machine, of which the following is
a specification.

This invention relates to washing-ma-
chines, and has for its object to simplify and
10 improve the construction and increase the
efficiency without increased expense or com-
plication of the parts.

With these and other objects in view,
which will appear as the nature of the inven-
15 tion is better understood, the same consists
in certain novel features of construction as
hereinafter fully described and claimed.

In the accompanying drawings, forming a
20 part of this specification, and in which corre-
sponding parts are denoted by like designat-
ing characters, is illustrated the preferred
form of the invention capable of carrying the
same into practical operation, it being un-
25 derstood that the invention is not necessarily
limited thereto, as various changes in the
shape, proportions, and general assemblage
of the parts may be resorted to without de-
parting from the principle of the invention or
30 sacrificing any of its advantages, and the
right is therefore reserved of making all the
changes and modifications which fairly fall
within the scope of the invention and the
claims made therefor.

In the drawings thus employed, Figure 1
35 is a sectional side elevation of the improved
apparatus. Fig. 2 is a plan view in section
on the line 2 2 of Fig. 1. Fig. 3 is a perspective
view of the movable rubber member and
its operating-lever arm detached.

40 The receptacle for the clothes to be washed
will preferably be formed with sheet-metal
bottom 10 and side walls 11, with a wooden
top 12, pierced for a closing-cover 13, hinged
at one side, as at 14, to the top and likewise pro-
45 vided with a wringer-supporting bracket 15.

Disposed upon the bottom 10 are radiating
rubber ribs 16, and extending vertically upon
the side walls 11 are spaced rubbing-ribs 17.

50 Pivotedly connected with the cover 13, as
by means of loops or eyes 18, is a frame 21 of
approximately rectangular shape, said frame
being preferably formed of a single piece of
wire the ends of which are bent upward ad-
55 jacent to each other and connected by means
of a collar 20, so as to form an arm or shank
19, which extends through a slot 24 in the

cover. The ends of the members forming
the shank 19 are extended laterally to form
arms 23, which are pivotally connected with
an operating frame or handle. (Seen in side 60
elevation in Fig. 1 of the drawings.)

Pivotedly mounted upon the lower mem-
ber of the rocking frame 21 is a rubbing-
frame 26, composed of side members 26^a,
resting upon a base 26^b and abutting upon 65
each other at their front ends in the form
of an isosceles triangle. This frame is pro-
vided with loops or staples 27, extending
both downwardly and laterally, the laterally-
extending staples serving as connecting 70
means for the side members of the frame with
each other and with the base. Said staples
or loops also serve to form a rubbing-surface,
whereby the clothes that are to be washed will
be actively engaged. The said rubbing- 75
frame is mounted, as stated, to swing pivot-
ally upon the lower member of the frame 21;
but it is of such dimensions that it will not
rotate completely within said rocking frame.
The triangular shape of the rubbing-frame is 80
considered of great importance in the con-
struction of the device, inasmuch as said
frame serves as a wedge which on its forward
movement will divide the contents of the
tub or receptacle, thus causing every gar- 85
ment contained in the receptacle to be oper-
ated upon by the rubbing device.

The dimensions of the frame 21 are such that
the rubber member will be maintained at a
sufficient distance above the rubber ribs 16 90
to prevent direct contact therewith, but suf-
ficiently close thereto to effect the proper ac-
tion on the clothes. By this arrangement
when the clothes, together with the requisite
water and detergent material, are placed in 95
the receptacle and the cover 13 closed and
the arm reciprocated by means of the handle
25 the rubber member will press upon the
clothes and rub them thoroughly back and
forth over the rubber ribs and effectually re- 100
move all adhering particles of dirt there-
from and without injury to the garments.

The device is simple in construction, can
be inexpensively manufactured, and will
quickly and thoroughly wash the clothes de- 105
posited in the receptacle.

Having thus described the invention, what
is claimed is—

1. In a washing-machine, a receptacle hav-
ing a hinged cover, a rocking frame connected 110
with said cover and having a shank extending
through a slot therein and provided with a

handle, and a wedge-shaped rubbing-frame of the shape of an isosceles triangle connected pivotally with the rocking frame.

2. In a washing-machine, a receptacle having interiorly-disposed rubbing members, a rocking frame supported in said receptacle, and a wedge-shaped rubbing-frame of the shape of an isosceles triangle connected pivotally with said rocking frame.
- 10 3. In a washing-machine, a rubbing-frame in the shape of an isosceles triangle having side members abutting upon each other and

upon a base, and staples connecting said side members with each other and with the base and extending laterally from the parts connected thereby to form clothes-engaging rubbing-surfaces.

In testimony that I claim the foregoing as my own I have hereto affixed my signature in the presence of two witnesses.

JOSEPH G. KINCAID.
